UNITED STATES PATENT OFFICE.

SAMUEL VLANCH, OF SIOUX CITY, IOWA.

FIREARM.

1,348,910.

Specification of Letters Patent. Patented Aug. 10, 1920.

Application filed March 26, 1920. Serial No. 368,933.

To all whom it may concern:

Be it known that I, SAMUEL VLANCH, a subject of the King of Serbia, and a resident of Sioux City, in the county of Woodbury and State of Iowa, have invented certain new and useful Improvements in Firearms, of which the following is a specification.

My invention has for its primary object the production of a fire arm support 10 adapted to be carried by a person, and so constructed as to properly aim and discharge the weapon as the person raises his arm in obeying the command of a bandit.

A further object of the invention is the 15 production of a fire arm support adapted to be readily secured to a person's body and controlled by movement of a limb of the person, to aim and discharge the weapon.

With these and other objects in view the 20 invention will be clearly understood from the structure hereinafter described, defined in the appended claims, and illustrated in the accompanying drawings, which form a part of this application, and in which like 25 characters of reference indicate corresponding parts throughout the several views, of which,--

Figure 1 is a side elevation of the device of my invention as secured to a person's 30 body;

Fig. 2 is an enlarged side elevation of the oscillating support and associated parts;

Fig. 3 is a front elevation of the same, a portion of the belt being shown;

Fig. 4 is a perspective view of the controlling means; and

Fig. 5 is a side elevation thereof.

While I have illustrated, and hereinafter described the preferred embodiment of the 40 invention, I would not be understood as being limited to the specific structure chosen for illustration, for many alterations and modifications may be made in the details of construction and arrangement of parts 45 herein disclosed, without departing from the spirit and scope of the invention, as defined in the appended claims.

My invention contemplates, broadly, a device including a base part adapted to be 50 secured to a person's body and having mounted to oscillate thereon, a fire arm support. The base is provided with a trigger engaging element, and the weapon support is adapted to be so connected with a limb 55 of the wearer that movement of the limb raises the support to firing position and

causes the trigger engaging element to fire the weapon, all of which will presently be made clear.

Referring now to the illustrations, 6, is a belt adapted to encompass the torso of the person and having fixed thereto the base consisting of a plate, 7, of any preferred shape. On the central portion of the plate, 7, is suitably pivoted, as at 8, a revolver support consisting of a plate, 9, adjacent which a revolver may be placed and preferably having the general contour of the weapon. The rear end portion of the plate, 9, I provide with one or more laterally and forwardly turned ears, 10, and a lower laterally and upwardly bent ear, 11, the said ears being so shaped and related as to engage the rear and bottom of the revolver stock to prevent rearward, downward and lateral 70 movement of the stock, a lateral ear, 12, being provided on the plate, 9, engageable with the front of the stock to prevent forward displacement thereof.

The front end portion of the plate, 9, extends a distance forwardly from the base, and on its adjacent side carries a plate, 13, secured by a pin or rivet, 14, to a lug, 15, on the opposite side of the plate, 9, the latter plate being longitudinally slotted, as at 16, 80 to receive the rivet, 14, and permit forward and rearward movement of the plate, 13. The front end of the plate, 13, is provided with a lateral head, 17, which extends through a longitudinal slot, 18, in the plate, 9, and is provided with upper and lower grooves, 19, which slidably receive the adjacent edges of the plate, 9.

The head, 17, is formed with a collar, 20, so positioned that when the plate, 13, is extended forwardly and the revolver is placed in position against the plate, 9, the collar, 20, will be alined coaxially with the end of the barrel, then when the plate, 13, is moved rearwardly the collar slips over the end of the barrel, thus holding the revolver against displacement.

For the control of the barrel engaging mechanism I provide a lever, 21, fulcrumed, as at 22, on the plate, 9, and having depending cams, 23, positioned, respectively, in the front and rear of the lug, 15, by virtue of which construction depression of the rear end of the lever, 21, causes the rear cam, 23, to coact with the lug to force the collar forwardly while depression of the opposite end of the lever, 21, causes movement of the

collar in the opposite direction. The collar is preferably held yieldably in its rearmost position by means of a leaf spring, 24, suitably secured, as at 25, to the plate, 9, and 5 engaging the front end portion of the lever, 21, thus holding the lever normally depressed at its front end.

Below the pivot, 8, the plate, 9, is provided with an arcuate slot, 26, through which extends 10 a lug, 27, carried by the base and positioned in front of the trigger.

To the base is secured an upwardly extending arm, 28, adapted to rest against the side of the wearer and extend approximately 15 to the arm pit, and to its upper end is hinged, as at 29, an arm, 30, provided with spring clips, 31, adapted for engagement with the wearer's upper arm, and between the arm, 30, and the front end of the plate, 20 9, is a flexible link, 32.

Normally, the weapon hangs downwardly from the belt, as shown in dotted lines in Fig. 1, but when the wearer lifts his arm, as shown, it is clear the oscillating support 25 will be so lifted that the revolver assumes approximately a horizontal position, and as the arm is lifted slightly higher the trigger engages the lug, 27, to fire the revolver.

Having thus described my invention, what 30 I claim as new and desire to secure by Letters Patent of the United States is:—

1. A device of the class described comprising a base part adapted to be secured to a person's body, an oscillating fire-arm supporting part carried thereby, an element carried by the base part to engage and operate the trigger of the fire-arm when the supporting part is oscillated, and means for oscillating the latter part.

40 2. A device of the class described comprising a base part adapted to be secured to a person's body, an oscillating fire-arm supporting part carried thereby, an element carried by the base part to engage and operate the trigger of the fire-arm when the supporting part is oscillated, and means for oscillating the latter part including a link having one end secured to the latter part and the other adapted to be secured to a 45 50 movable part of the person's body.

3. A device of the class described comprising a base plate adapted to be secured to a person's body, a revolver support pivoted on the plate to swing upwardly and downwardly, an element on the plate to engage and operate the revolver trigger when the support is swung upwardly, and means for swinging the support upwardly.

4. A device of the class described comprising a base plate adapted to be secured to a person's body, a revolver support pivoted on the plate to swing upwardly and downwardly, an element on the plate to engage and operate the revolver trigger when the support is swung upwardly, and means for swinging the support upwardly including a tactile member secured to the support and adapted to be secured to a person's limb.

5. A device of the class described comprising a base plate adapted to be secured to a person's body, an oscillating support thereon to which a revolver may be removably secured, a projection on the plate to operatively engage the revolver trigger, when the support is oscillated, and means for oscillating the support.

6. A device of the class described comprising a base plate adapted to be secured to a person's body, an oscillating plate pivoted on the base plate to swing upwardly and downwardly, means for removably securing a revolver on the second plate, the second plate having a slot, a lateral projection on the base plate extending through the slot to operatively engage the revolver trigger when the second plate is swung upwardly, and means for swinging the second plate upwardly.

7. A device of the class described comprising a base plate adapted to be secured to a person's body, an oscillating plate pivoted on the base plate to swing upwardly and downwardly, revolver stock and barrel engaging means on the second plate, trigger operating means governed by swinging of the second plate, and means for swinging the second plate.

In testimony whereof I have hereunto set my hand this 4th day of March, 1920.

SAMUEL VLANCH.
